UNITED STATES PATENT OFFICE.

HARRY WEARNE, OF RIXHEIM, GERMANY.

DESIGN FOR WALL-PAPER.

SPECIFICATION forming part of Design No. 31,957, dated December 5, 1899.

Application filed November 11, 1899. Serial No. 736,692. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a plan view of a strip of wall-paper embodying the features of my design.

The leading feature of the design consists of a floral chain composed of the representation of flowers of the hollyhock type, their buds, and stems.

In detail the design consists in flowers representing hollyhocks, their buds, branches, and stems so grouped that a floral chain is obtained, which chain appears between parallel borders, including straight and decorative panel-sections.

Having thus described my invention, I claim as new and desire to secure by Letters Patent—

The design for wall-paper as herein shown and described.

HARRY WEARNE.
